(57) **CLAIM**

The ornamental design for a self fitting lug for a firearm mount, as shown and described.

DESCRIPTION

FIG. 1 is a top front perspective view of self fitting lug for a firearm mount showing my new design;

FIG. 2 is a bottom front perspective view thereof;

FIG. 3 is a front elevation view thereof;

FIG. 4 is a rear elevation view thereof;

FIG. 5 is a right elevation view thereof, with the left elevation view being a mirror image thereof;

FIG. 6 is a top plan view thereof; and,

FIG. 7 is a bottom plan view thereof.

The broken lines shown in the drawings illustrate portions of the self fitting lug for a firearm mount that form no part of the claimed design.

1 Claim, 3 Drawing Sheets(56)
